BLOOD PUMP

Clarence Edwin Schmidt, 2741 E. Palmyra,
Orange, Calif. 92669

Filed Dec. 6, 1972, Ser. No. 312,761

Term of patent 14 years

Int. Cl. D24—01; D15—02
U.S. Cl. D83—1 F

FIG.1

FIG.2

FIG.3

FIG.4

FIG.5

FIG.6

FIG. 1 is a front perspective view of a blood pump showing my new design;

FIG. 2 is a side elevation thereof;

FIG. 3 is a front elevation thereof;

FIG. 4 is a rear elevation thereof;

FIG. 5 is a top plan view thereof; and

FIG. 6 is a bottom plan view thereof.

I claim:

The ornamental design for a blood pump, substantially as shown and described.
